COMBINED AMPLIFIER AND TUNER THEREFOR

Hitoshi Mukai, Tokyo, Japan, assignor to Sansui
Electric Co., Ltd., Tokyo, Japan

Filed Oct. 19, 1973, Ser. No. 408,020

Claims priority, application Japan May 29, 1973

Term of patent 14 years

Int. Cl. D14—03

U.S. Cl. D26—14 L

FIG. 1

FIG. 3

FIG. 1 is a front elevation of a combined amplifier and tuner therefor, showing my new design;

FIG. 2 is a front perspective thereof; and

FIG. 3 is a rear perspective thereof.

Portions of the view are shaded to indicate contrasting color.

I claim:

The ornamental design for a combined amplifier and tuner therefor, as shown and described.
